**CAPTIVE CAP FOR COLLAPSIBLE TUBES
OR THE LIKE**

Albert H. Torongo, Jr., Yardley, Pa., and Paul R. Campbell, Cincinnati, Ohio, assignors to The Procter & Gamble Company, Cincinnati, Ohio, a corporation of Ohio

Filed Nov. 4, 1968, Ser. No. 14,290

Term of patent 14 years

Int. Cl. D9—02

U.S. Cl. D9—275

FIG. 1 is an elevational view of a captive cap for collapsible tubes or the like, showing our new design;

FIG. 2 is a cross sectional view on a reduced scale from FIG. 1, taken on the line 2—2 of FIG. 3;

FIG. 3 is a bottom plan view thereof on a still smaller scale; and

FIG. 4 is a top plan view thereof, on the same scale as FIG. 3.

We claim:

The ornamental design for a captive cap for collapsible tubes or the like, as shown.
